BELL TOP FOR FILLING VALVES

Chester Sylvester Mullenix, Pittsburgh, Pa., as signor to The Liquid Carbonic Corporation, Chicago, Ill., a corporation of Delaware

Application March 20, 1939, Serial No. 262,830

10 Claims. (Cl. 226—129)

The present invention relates to improvements in valves for bottle filling apparatus of the type adapted to deposit carbonated water, beer, or a similar material, in the bottles.

As a rule, in machines of this character, there is provided a rotary head in which the liquid to be flowed into the bottle is contained, and this head carries a series of valves or filling heads, each of which is adapted to contact a bottle and deposit sufficient contents therein to fill the bottle or container to the desired point.

As a rule, for the purpose of operating the filling valve, the bottles are, through a suitable cam mechanism, during their rotative movement, raised and lowered to receive a filling tube of the valve and operate suitable mechanism to permit the liquid to flow therein.

One of the objects of the present invention is to provide a bell top or bottle engaging member for a filling valve which may be readily removed from its associated parts, for the purpose of cleaning, not only the bell top itself but certain of the parts of the filling valve and which also will reduce the jar or impact so frequently accompanying the rapid movement of a device of this character.

For the purpose of disclosing the invention, I have illustrated an embodiment thereof in the accompanying drawing, in which:

Fig. 1 is a longitudinal sectional view of a filling valve embodying my invention; and

Fig. 2 is a transverse sectional view on the line 2—2 of Fig. 1.

Referring to the structure illustrated in the accompanying drawing, the valve and accompanying mechanism comprises a base 1 which is connected to and forms a part of the bottom of the, as a rule, annular tank of the filling machine. Extending downwardly from this base 1 is a filling tube 2 adapted, as the bottle is raised by the cam mechanism, to be projected into the bottle to a point near the bottom. This tube communicates with the interior of the liquid supply tank and has its lower end normally closed through the medium of a pear-shaped valve 3 which is secured to the lower end of an operating stem or rod 4. The upper end of this stem or rod is connected, through a suitable discon-nectible joint 5 with a diaphragm 6 arranged in a chamber 7. This chamber, above the dia-phragm, communicates with the tubes 8 between the base portion 1 and a head 11 which, in turn, has clamped above the top a supplemental head 12 between which and the head 11 is clamped the diaphragm.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

When the operating stem 4 is moved upwardly, the diaphragm 6 is caused to move upwardly and the upper portion of the tube 8 is closed off by the valve 3.

When the operating stem 4 is moved downwardly, the diaphragm 6 is caused to move downwardly and the upper portion of the tube 8 is opened by the valve 3.

opening of this valve admits pressure through the ports 35 to the chamber 8 and thence through suitable passages 36 above the diaphragm 6, therefore causing an opening of the pear-shaped valve 3 and permitting the flow of the filling liquid into the bottle. After the liquid level has reached the predetermined point in the bottle, the bottle commences to descend and, as the result of its descending movement, shuts off the flow of liquid thereinto. With the descent of the bottle, of course the bell top descends and is eventually stopped by engagement of the hub 30 with the ferrule 26.

The reciprocating movement of the bottle in this type of filling machine is comparatively rapid, particularly on its downward movement, and heretofore difficulty has been experienced as a result of said downward movement in the bell top head striking its bottom limiting stop with such a jar as to not only tend to damage the parts but also tend to cause foaming of the contents of the tube. The liquid discharged into the bottle through the filling tube is as a rule a carbonated beverage of some character, beer, carbonated water for carbonated beverages, or the like. A sudden jar of the liquid contained in the tube after the pear-shaped valve 3 has been closed, will tend to liberate the CO₂ in this column of liquid and therefore, as soon as the next bottle is in a filling position, this agitated column of liquid with a certain amount of CO₂ liberated therein will flow into the bottle, causing a foaming of the contents therein, particularly where the liquid is admitted on top of a syrup. This is particularly true with respect to beer. Due to the fact that, in the present structure, the jar or shock of the stopping movement of the bell top is taken up by the spring 33 no such jar or impact is imparted to the column of liquid in the filling tube 2 and therefore the liquid contained therein remains in its quiescent state.

If, for any reason, it becomes necessary to remove the bell top head 21 and its associated parts, from the filling tube 2, the centering bell 22 may be unscrewed from the top section 24 carrying with it the sealing rubber 23 and associated washer 32', the top section 24 may then be raised on the tube 2 exposing the split ring 21. By removing the coiled spring 33 from the sleeve portion 31, the split ring may be separated and removed from the filling tube 2, after which the spring 33 and top portion 24 may be slid down over the end of the tube and over the ferrule 26. The opening 25 in the top portion 24 and the spring 33 are sufficiently large to pass over this ferrule 26.

Due to the fact that the bell head 21 may be so readily removed and due to the fact that the valve member 15' is threaded on the extension 14, the valve member, with its associated valve parts, may also be readily removed for cleaning, repair, etc., without removing the filling tube 2 which can remain closed and thus the necessity of draining the filler tank for the purpose of repair of these parts is avoided.

I claim as my invention:

1. In a filling valve for container filling machines, the combination with a filling tube adapted to be projected into the container to be filled, of a bell top adapted to engage and seal the neck of the container to be filled surrounding and reciprocating upon said filling tube, a ferrule secured at the lower end of said tube, a removable ferrule engaging member arranged in said bell top adapted to engage said ferrule and a spring

interposed between said ferrule engaging member and said bell top to absorb the shock of said engagement.

2. In a filling valve for container filling machines, the combination with a filling tube adapted to be projected into the container to be filled, of a bell top adapted to engage and seal the neck of the container to be filled and having an opening therethrough to accommodate the passage of said filling tube, an annular stop member secured to the bottom end of said tube, the opening through said bell top being greater in diameter than said annular stop member, a removable reciprocating member arranged within said bell top member having an opening of smaller diameter than said annular stop member and adapted to engage said annular stop member to limit the downward movement of said bell top member, and a spring interposed between said annular stop engaging member and the bell top member.

3. In a filling valve for container filling machines, the combination with a filling tube adapted to be projected into the container to be filled, of a bell top adapted to engage and seal the neck of the container comprising a housing surrounding and reciprocating upon said tube, and a bell mouth secured to said housing, an annular stop member secured to the lower end of said tube, an axially movable separable stop engaging member arranged within said housing having an opening for the passage of said tube smaller in diameter than said annular stop, and a coiled spring interposed between the top of said housing and said stop engaging member.

4. In a filling valve for container filling machines, the combination with a filling tube adapted to be projected into the container to be filled, of a bell top adapted to engage and seal the neck of the container to be filled, comprising a bell mouth and a housing having axially aligned openings therein to permit the passage therethrough of the delivery tube, an annular stop member mounted on the lower end of said tube, said axially aligned openings being of greater diameter than said annular stop member, a separable reciprocating stop engaging member arranged within said housing having an opening therein smaller in diameter than said annular stop but sufficiently large to accommodate said tube and comprising an annular piston fitting within and vertically movable in said housing and having extending therefrom a restricted neck and a coiled spring surrounding said neck and interposed between said piston and the top of said housing.

5. In a filling valve for container filling machines, the combination with a filling tube adapted to be projected into the container to be filled, of a bell top surrounding said tube and adapted to engage and seal the neck of the container to be filled, comprising a bell mouth and a housing separably connected together and having axially aligned openings therein to permit the passage therethrough of the delivery tube, an annular stop secured on the lower end of the tube, said axially aligned openings being of greater diameter than the annular stop member, a split ring arranged within said housing having an opening therein smaller in diameter than the annular stop but sufficiently large to accommodate the tube, and a coiled spring interposed between said ring and housing.

6. In a filling valve for container filling machines, the combination with a filling tube adapt-

ed to be projected into the container to be filled, of a bell top surrounding said tube and adapted to engage and seal the neck of the container to be filled, comprising a bell mouth and a housing separably connected to said bell mouth having axially aligned openings to permit the passage therethrough of the delivery tube, a stop member mounted at the lower end of said tube, said axially aligned openings being of greater diameter than the stop member, a split stop-engaging member surrounding said tube having a sleeve, and a coiled spring surrounding said sleeve and interposed between the stop engaging member and the housing.

7. In a filling valve for container filling machines, the combination with a filling tube adapted to be projected into the container to be filled and having an enlarged ferrule at the lower end thereof, of a bell top adapted to engage and seal the container to be filled and having an opening in the top thereof to permit the passage therethrough of said ferrule and removable ferrule-engaging means surrounding said tube, of greater diameter than said opening for normally preventing said bell top from dropping off the end of said tube when a container is removed from beneath the same and comprising separable segments.

8. In a filling valve for container filling machines, the combination with a filling tube adapted to be projected into the container to be filled and having an enlarged ferrule at the lower end thereof, of a bell top adapted to engage and seal the container to be filled and having an opening in the top thereof to permit the passage therethrough of said tube, a removable ferrule-engaging means surrounding said tube and of greater diameter than said opening and resilient means interposed between said ferrule-engaging means and said bell top.

9. In a filling valve for container filling machines, the combination with a filling tube adapted to be projected into the container to be filled, of a bell top adapted to engage and seal the neck of the container to be filled comprising a bell mouth and a housing having axially aligned openings therein to permit the passage therethrough of the delivery tube, an annular stop member mounted on the lower end of said tube, said axially aligned openings being of greater diameter than said annular stop member, and a separable reciprocating stop-engaging member arranged within said housing having an opening therein smaller in diameter than said annular stop but sufficiently large to engage said tube and having a portion adapted to be engaged by said housing to normally prevent the removal of said bell mouth from said tube.
10. In a filling valve for container filling machines, the combination with a filling tube adapted to be projected into the container to be filled, of a bell top surrounding said tube and adapted to engage and seal the neck of the container to be filled comprising a bell mouth and a housing separably connected together and having axially aligned openings therein to permit the passage therethrough of the delivery tube, an annular stop secured to the lower end of the tube, said axially aligned openings being of greater diameter than the annular stop member and a split ring arranged within said housing having an opening therein smaller in diameter than the annular stop but sufficiently large to accommodate the tube and having a portion adapted to be engaged by said housing to normally prevent the removal of the same from said tube.

CHESTER SYLVESTER MULLENIX.
